(Cl. D45—4)

To all whom it may concern:

Be it known that we, Leon Wertheimer and Roger J. Van Craeynest, both citizens of the United States, residing at San Francisco, in the county of San Francisco and State of California, have invented a new, original, and ornamental Design for a Link, of which the following is a specification, reference being had to the accompanying drawing, forming part thereof.

In the drawing

Fig. 1 is a top plan view of a link showing our new design;

Fig. 2 is a bottom plan view thereof;

Fig. 3 is a front elevational view thereof; and

Fig. 4 is a side elevational view thereof.

We claim:

The ornamental design for a link, substantially as shown.

LEON WERTHEIMER.

ROGER J. VAN CRAEYNEST.
